UNITED STATES PATENT OFFICE.

THOMAS SHIPLEY, OF YORK, PENNSYLVANIA, ASSIGNOR, BY MESNE ASSIGNMENTS,
TO YORK ICE MACHINERY CORPORATION, OF YORK, PENNSYLVANIA, A CORPORA-
TION OF DELAWARE.

EVAPORATOR.

Application filed January 21, 1927. Serial No. 162,574.

This invention relates to refrigeration, and particularly to the construction and arrangement of the evaporators. In the past the advantage of operating an evaporator 5 flooded was fully understood, but efforts so to operate them have not proved uniformly successful and the installations have generally been limited to cases where some type of receiver could be located above the evaporator and then feed it by gravity. A known arrangement is to make use of what is termed a suction trap as the reservoir which feeds the coils, the separation of the vapor and the return of the liquid to the 10 suction trap occurring through the action of gravity.

The purpose of the present invention is to produce an installation in which a plurality of units may be operated in parallel, may 20 be defrosted individually, may be adjusted individually for refrigerative effect, and in which substantially flooded operation is insured at all times.

The invention is particularly adaptable 25 to hardening rooms for ice cream, cold storage, and similar plants, and may be also embodied in brine tanks for freezing ice in cans, brine coolers and the like.

It has heretofore been proposed to circulate liquid refrigerant through an evaporator by a pump or equivalent means, for the purpose of maintaining the evaporator substantially flooded, that is to say, for the 30 purpose of insuring that liquid refrigerant penetrates throughout substantially the entire length of the evaporator. In such prior devices the receiver has been mounted above the evaporator, the idea being to keep the evaporator submerged in liquid by the existence of a static head rather than by the action of the pump alone.

The present case is directed to a particular embodiment of the positive circulation idea, in which the refrigerant is so circulated that 45 it first enters the top of the evaporator, flows thence downwardly through the evaporator and returns from the evaporator with sufficient velocity to entrain with the liquid refrigerant the vapor formed in passage 50 through the evaporator. The receiver then acts as a suction trap in which the liquid and vapor separate, the vapor passing to the suction line of the compressor and the liquid being recirculated by the pump.

This arrangement has various advantages. 55 By making the circulation sufficiently rapid the liquid flow will persist to the lower end of the evaporator and will be effective to entrain the evolved vapor and sweep it out of the evaporator even though a substantial 60 portion of the cross section of the evaporator be not filled with the liquid but remain clear for the passage of the vapor. Another advantage is that when the pump is shut down the evaporator drains, producing a condition 65 favorable to defrosting of the evaporator on occasion.

In order to insure equal distribution of the refrigerant not only to different evaporators of a group but also to each element, 70 such as the individual coils of each evaporator, use is made of overflow distributors, so contrived as to insure approximately uniform feeding of all coils with liquid refrigerant. In order to regulate the action of the 75 evaporators, particularly where a plurality of these are connected up in parallel to a single compressor, use is made of a short circuiting by-pass, by means of which effective circulation produced by the pump may be reduced at will. This avoids any throttling of 80 the liquid refrigerant in the circulating flow, and is an important feature, leading to smooth operation and close control.

Three practical embodiments of the invention are illustrated in the accompanying 85 drawings, in which,

Fig. 1 is an elevation showing all the connections for two hardening rooms, fed by means of a single refrigerant cycle. In this 90 view the compressor, condenser and receiver are indicated by conventional diagram, in order to make clear the pipe connections to these elements.

Fig. 2 is a fragmentary view of one of 95 the coils of the evaporators illustrated in Fig. 1.

Fig. 3 is a transverse section of a distributing header on an enlarged scale, showing the construction of the flow distributors. 100

Fig. 4 is a diagrammatic elevation showing the application of the invention to cold storage rooms.

Fig. 5 is a diagrammatic section showing the application of the invention to a brine 105 cooler.

Referring first to Figs. 1, 2 and 3, 6 represents a liquid cooling trap to which liquid

refrigerant comes by way of the pipe 7 and float valve 8 from a high pressure receiver. The purpose of the float valve 8 is to maintain a constant level within the liquid cooling trap 6. The valve 9 is an ordinary stop valve in the liquid line. The valve 10 controls an oil drain wherever it appears. Pipe 11 is a suction connection from the trap 6 and leads to the interstage connection of a two stage compressor. This compressor is indicated by the legend "L. P." applied to its lower pressure cylinder, and the legend "H. P." applied to the high pressure cylinder. The condenser is indicated by the letter "C" and the high pressure receiver by the legend "H. P. R." It is to be understood that the compressor is of any known variable capacity type. The compressor, condenser and receiver are diagrammatically illustrated merely to show the evaporator connections clearly. No novelty is claimed broadly for the use of a variable capacity compressor or for the particular arrangement of the compressor and its connections. In fact these are subject to considerable change without departing from the inventive principle here involved.

Inasmuch as Fig. 1 shows two cooling rooms connected up in parallel, the same reference numerals will be applied to corresponding elements for each room designated generally by the legends "Room A" and "Room B".

Pipe 12 leads from the trap 6 by way of stop valve 13 and float valve 14 to a suction trap 15. The purpose of the float valve 14 is to maintain a constant level of liquid refrigerant in the trap 15. Leading from the bottom of the trap 15 is a pipe 16 which is controlled by valve 17 and leads to a rotary pump 18 driven in any desired manner. This pump discharges through valve 19 to a line 20 which leads to a distributing manifold 21. A by-pass between the pipes 20 and 16 is controlled by by-pass valve 22. For defrosting there is provided a hot gas connection 23 controlled by a stop valve 24, and since during the defrosting operation the suction trap 15 might receive an excess of liquid refrigerant, a reversed float valve 25 is provided. The reversed float valve 25 controls flow through the pipe connection 26 back to the cooler 6.

Under normal conditions, as will be understood, the trap 15 is at a lower pressure than the trap 6, but, as will be later explained, this pressure relation is reversed during defrosting, and consequently the valve 25 is provided and so arranged that if the level of liquid rises unduly high in the suction trap 15 it will open to permit flow through the pipe 26 back to the cooling trap 6. This connection is provided with a hand operated stop valve 27 for emergency

use, and there is also a direct drain connection from the suction trap 15 to the pipe 26 controlled by stop valve 28, which is normally closed.

The manifold 21 is simply a drum into which project distributing pipes 29 having a row of graduated perforations 30 so designed that as the level of the liquid refrigerant in the manifold 21 rises, the rate of outflow will be increased to compensate. There are a plurality of pipes 29 in each manifold 21, one for each evaporator in the room. Thus in the manifold of Room A there are two sets of pipes and in Room B there are three sets of pipes. Each pipe 29 leads to the distributing manifold 31 of an evaporator, consisting of a plurality of evaporator coils 32 extending in a sinuous path and discharging at their lower ends into an off-take header 33. The manifold 21, the manifold 31 and the header 33 are all in communication with each other through a pressure equalizing connection 34 which enters the manifolds 21 and 31 above the liquid level therein. The headers 33 are connected by an off-take line 35 with the suction trap 15 above the liquid level therein. The pipe 36 controlled by a stop valve 37 leads to the suction connection 38. This is connected, of course, to the low pressure stage of the compressor.

Under normal conditions of operation the following valves are open, 9, 13, 17, 19, 27 and 37. At the same time the following valves are closed, 10, 24 and 28. The valve 22 is wholly or partly open according to the rate of circulatory flow desired to maintain the proper temperature in the corresponding coils 32. If it be desired to defrost the coils in either room, corresponding valves 19, 22 and 37 are closed, and the valve 24 is opened to admit hot gas from the compressor line to the pipe 20. At this time the pump 18 is, of course, out of operation. The effect is to displace the liquid refrigerant from the coils 32 causing it to flow back to the suction trap 15. Inverted float valve 25 guards against the accumulation of an excess of liquid refrigerant in the trap 15. Any such excess is returned to the trap 6. This occurs because under the conditions just recited trap 15 is at compressor discharge pressure. When defrosting is complete the valve 24 is closed and the valves 37, 19 and 22 are again reopened and the pump 18 started.

It will be observed that the coils of either room may be defrosted without interfering with the action of the coils in the other room, and that the circulatory rate for either room may be adjusted without affecting the circulatory rate for the other room. Concurrent adjustments of the capacity of the compressor are, of course, desirable.

The structure shown in Fig. 4 involves a

single stage compression. Consequently there is no liquid cooling trap and no reversed float valve connection. Instead, the liquid line 42 from the receiver leads through 5 a stop valve 43 to a float valve 44 which controls the liquid level in the suction trap 45, essentially identical in function to the suction trap 15. Liquid connection 46 leads through valve 47 and circulating pump 48 from which connection to the discharge line 50 is controlled by valve 49. The capacity 10 of the pump 48 is controlled by by-pass valve 52. Pipe 50 leads to a distributing header 51. There are a plurality of perforated distributor pipes 53, each of which acts to control the flow of liquid refrigerant to a corresponding coil 54, of which only one is indicated in the drawing. These coils discharge into a manifold 55 from which pipe 20 56 leads to trap 45.

The suction connection is shown at 57 and is controlled by a stop valve 58. 59 is a valve controlling a hot gas connection for defrosting.

25 In Fig. 5 the application of the device to a brine cooler for use in brine tanks and elsewhere, is illustrated. In this figure the parts are all substantially similar to those shown in Fig. 4 and are similarly numbered. 30 It will be observed that hot gas connections for defrosting are not necessary and are omitted. The brine tank is shown at 60.

In all three forms of the device, the flow 35 to the various coils is equalized by an over-flow or weir device, and the circulation is intentionally made so rapid that the vapor evolved in the evaporator can not rise through the descending current of liquid refrigerant, but is swept downwardly and out 40 with the liquid refrigerant, from which it separates in the suction trap. The operation of the device, therefore, entails a definitely maintained circulation which may actually be as much as four or five 45 times the quantity of liquid refrigerant which can be evaporated in a single pass through the evaporator. This insures a practically flooded condition of the evaporator at all times so that the entire surface 50 of the evaporator is rendered unusually effective.

What is claimed is,—

1. In a refrigerating system, the combination of a receiver and an evaporator connected to establish a closed circuit, the evaporator offering a plurality of flow paths in parallel arrangement; graduated over-flow distributing means arranged to equalize the flow through said parallel paths; power circulating means for circulating liquid refrigerant in said circuit; a connection for withdrawing vaporized refrigerant from the evaporator; and a connection for supplying liquid refrigerant to said circuit.

2. In a refrigerating system, the combination of a suction trap; an evaporator located in a position above the same; connections establishing a closed circuit from the lower portion of the suction trap to the top of the evaporator thence downward through the evaporator and from the bottom of the evaporator to the suction trap; power circulating means for positively circulating liquid refrigerant in said closed circuit, in a quantity substantially in excess of that evaporable in the evaporator whereby the vapor evolved in entrained by the off-flowing liquid refrigerant; a suction connection leading from the upper part of said suction trap; and a connection for supplying liquid refrigerant. 65 70 75 80

3. In a refrigerating system, the combination of a receiver and an evaporator connected to establish a closed circuit, said evaporator including a plurality of units connected in parallel, each unit comprising a plurality 85 of tubes connected in parallel; primary over-flow distributing means arranged to equalize the flow of liquid refrigerant to the various units; secondary over-flow distributing means arranged to equalize the flow to the 90 various tubes of each unit; power circulating means for circulating liquid refrigerant through said circuit, under the control of said distributing means; a connection for withdrawing vaporized refrigerant from said 95 evaporator; and a connection for supplying liquid refrigerant to said circuit.

4. The combination of a variable capacity compressor; a condenser to which said compressor discharges; a plurality of evaporator 100 units each including an evaporator and a suction trap connected to form a closed circuit; power means corresponding to each circuit 105 for circulating volatile liquid refrigerant from the suction trap through the evaporator and back to the suction trap; means for adjusting the circulatory rate of each power circulating means independently; vapor suction connections leading from the respective circuits to the suction of said compressor; 110 and means for returning liquid refrigerant from said condenser to said circuits to compensate for evaporation therein. 115

5. The combination of a variable capacity compressor; a condenser to which said compressor discharges; a plurality of evaporator units each including an evaporator and a suction trap connected to form a closed circuit; power means corresponding to each circuit 120 for circulating volatile liquid refrigerant from the suction trap through the evaporator and back to the suction trap; an adjustable by-pass between the intake and discharge of each circulating means operable to vary the circulatory rate through the corresponding evaporator; vapor suction connections leading from the respective circuits to the suction of said compressor; and means 125

for returning liquid refrigerant from said condenser to said circuits to compensate for evaporation therein.

6. The combination of a variable capacity compressor; a condenser into which said compressor discharges; a plurality of independent evaporator circuits each including a suction trap; an evaporator and power circulating means for circulating volatile liquid refrigerant from the trap to the top of the evaporator, thence downward through the evaporator and back to the trap; overflow distributing means for maintaining uniform flow through the evaporators; means for adjusting each circulator to vary the circulatory rate in one circuit independent of that in another; a vapor suction connection from the various circuits to the compressor; and automatic means for delivering liquid refrigerant from the condenser to said circuits at rates commensurate with the evaporation of refrigerant in such circuits.

7. The combination of a two-stage variable capacity compressor having an interstage passage; a condenser into which the high pressure stage of said compressor discharges; a primary refrigerant cooler; a feed device for delivering volatile liquid refrigerant from the condenser to said primary cooler; a vapor suction connection from said cooler to the interstage passage of said compressor; an evaporator circuit consisting of an evaporator; a suction trap and a power circulating means for circulating volatile liquid refrigerant from the trap through the evaporator and back to the trap; an automatic valve device for supplying liquid refrigerant from said primary cooler to said trap at a rate commensurate with the evaporation in the evaporator; a vapor suction connection from the evaporator circuit to the low pressure stage of the compressor; and means for varying the circulatory rate in said circuit.

8. The combination of a two-stage variable capacity compressor having an interstage passage; a condenser into which the high pressure stage of said condenser discharges; a primary refrigerant cooler; automatic means for feeding liquid refrigerant from said condenser to said primary cooler; a vapor suction connection from said primary cooler to the interstage passage of said compressor; a plurality of independent evaporator circuits each consisting of an evaporator, a suction trap, and power operated means for circulating volatile liquid refrigerant from the trap through the corresponding evaporator and back to the trap; independent means for varying the circulatory rate of each circulating means; and a vapor suction connection from each evaporator circuit to the suction of the low pressure stage of the compressor.

9. The combination of a compressor; a condenser; a circuit including a suction trap, an evaporator mounted above said trap so as to drain to the trap, and a power actuated circulating means arranged to draw volatile liquid refrigerant from the trap and discharge it through the evaporator and back to the trap; a suction connection from the trap to the suction of the compressor; a stop valve controlling said connection; and a valve controlled connection for delivering hot gas from the compressor to said circuit.

10. The combination of a two-stage compressor; a condenser into which said compressor discharges; a primary cooler; means for delivering refrigerant liquefied in the condenser to the primary cooler; a vapor suction connection from the primary cooler to the interstage passage of said compressor; an evaporator circuit consisting of a suction trap, an evaporator arranged to drain by gravity into said trap and power actuated circulating means arranged to draw liquid from the trap and discharge it through the evaporator back to the trap; means for feeding liquid refrigerant from the primary cooler to the trap; a back-flow connection from the trap to the primary cooler; liquid level control means for opening said back-flow connection upon the existence of an unduly high level of refrigerant in the trap; a suction connection from the trap to the low pressure stage suction of said compressor; a stop valve controlling said suction connection; and a valve controlled connection for delivering hot gas from the compressor to said evaporator circuit.

11. In a refrigerating device, the combination of a circuit including a reservoir, an evaporator mounted above said reservoir so as to drain thereto, and a power actuated circulating means arranged to draw volatile liquid refrigerant from the reservoir and discharge it downward through the evaporator and back to the reservoir; a suction connection for withdrawing vapor evolved in the evaporator; a stop valve controlling said connection; and a valve-controlled connection for delivering hot gas to said circuit.

12. An evaporator comprising in combination, a manifold adapted to receive liquid refrigerant; and a plurality of tubes leading downward therefrom, the upper ends of said tubes projecting into said manifold and having lateral apertures through which liquid refrigerant enters the tubes from the manifold.

13. An evaporator comprising in combination, a manifold adapted to receive liquid refrigerant; and a plurality of tubes extending downward from said manifold, the upper ends of said tubes projecting through the bottom of the manifold into the same and to a point above the liquid level therein,

said projecting ends being formed with lateral perforations.

14. An evaporator comprising in combination, a manifold adapted to receive liquid refrigerant; and a plurality of tubes extending downward from said manifold, the upper ends of said tubes projecting through the

bottom of the manifold into the same and to a point above the liquid level therein, said projecting ends being formed with lateral ¹⁰ perforations graduated in size.

In testimony whereof I have signed my name to this specification.

THOMAS SHIPLEY.
